(57) **CLAIM**

The ornamental design for a sealing cap for a snap engagement dispensing assembly, as shown and described.

DESCRIPTION

FIG. 1 is a top front perspective view of a sealing cap for a snap engagement dispensing assembly, showing my new design;

FIG. 2 is a bottom front perspective view thereof;

FIG. 3 is a front view thereof;

FIG. 4 is a cross-sectional view thereof, taken along the line 4-4 of FIG. 3, and the opposite cross-sectional view being a mirror image thereof;

FIG. 5 is a right side view thereof, and the left side view being a mirror image thereof;

FIG. 6 is a rear view thereof;

FIG. 7 is a top plan view thereof; and,

FIG. 8 is a bottom plan view thereof.

The broken line portions show unclaimed subject matter only and form no part of the claimed design.

1 Claim, 4 Drawing Sheets
